UNITED STATES PATENT OFFICE.

FRANK JASPER ROGERS, OF DIAGONAL, IOWA.

DESIGN FOR A HARNESS-PAD.

SPECIFICATION forming part of Design No. 35,695, dated February 4, 1902.

Application filed December 21, 1901. Serial No. 86,860. Term of patent 14 years.

To all whom it may concern:

Be it known that I, FRANK JASPER ROGERS, a citizen of the United States, residing at Diagonal, in the county of Ringgold and State of Iowa, have invented and produced a new and original Design for a Harness-Pad, of which the following is a specification.

The invention relates to a new and original design for a harness-pad; and it has for its object to provide a design of this character which will be both useful and attractive.

The leading feature of the invention resides in the design forming the subject-matter of the accompanying illustration.

In the drawings, Figure 1 is a perspective view of a harness-pad, showing my new and original design. Fig. 2 is a reverse plan view of the same. Fig. 3 is a transverse sectional view.

Referring to the drawings, 11 designate two oblong approximately concavo-convex sides having rounded ends and curved both in cross-section and longitudinal section and presenting outer concave faces and having inner rounded convex faces. The inner con-

vex faces are rounded both transversely and longitudinally, and the sides, which have parallel intermediate upper edges, are set at an acute angle to each other and diverge downwardly. Also the end portions of the upper edges of the sides are curved and diverge, as shown. The sides are connected at the center of their upper edges by an approximately inverted-U-shaped yoke 2, having approximately vertical sides, which extend upward from the sides of the pad. The sides of the pad are provided with exterior oblong loops 3, arranged adjacent to the lower edges of the sides.

What I claim is—

The design for a harness-pad herein shown and described.

In testimony that I claim the foregoing as my own I have hereto affixed my signature in the presence of two witnesses.

FRANK JASPER ROGERS.
